FOLDING UNIT

Original Filed Sept. 17, 1927

UNITED STATES PATENT OFFICE

OSCAR CHARLES ROESEN, OF BROOKLYN, NEW YORK, ASSIGNOR TO WOOD NEWSPAPER MACHINERY CORPORATION, OF NEW YORK, N. Y., A CORPORATION OF VIRGINIA

FOLDING UNIT

Application filed September 17, 1927, Serial No. 220,161. Renewed November 29, 1930.

This invention relates to a newspaper printing machine folder for use principally in folding tabloids.

The principal objects of the invention are to provide an arrangement of the folding unit such that when folding tabloids the slit product can be run successfully into the folding unit from either side and the margins of the two halves of the web will register directly, and to eliminate the compensation rollers usually employed.

Other objects and advantages of the invention will appear hereinafter.

Reference is to be had to the accompanying drawings in which

Fig. 1 shows a folder arranged in accordance with this invention for receiving the webs from one side; and

Fig. 2 is a similar view showing the position for receiving them from the other side.

When running a newspaper product in a transverse collect run, that is, from both formers into a single folder unit it has been found very difficult, if not impossible, to run the product over compensating rollers when the product is slit over the former rolls as is the case in a tabloid newspaper.

In the ordinary practice the webs are run from the right hand former into the left hand folder, and vice versa, over compensating rollers. This works well enough for ordinary newspapers where the edge is folded. It cannot be done with a tabloid slit edge paper without causing too much puckering or gathering of some of the webs over the others.

I obviate this difficulty by eliminating the adjustable compensating rollers and employing a pair of nipping rolls on each folder unit over the folding rolls and movably independently of the formers. The split web is shiftable from one side to the other without moving the nipping rolls. It will be understood that a pair of nipping rolls, usually employed with each former, are retained in the same position as usual.

In the drawings, I have shown a construction comprising a pair of folding units 10. Each folding unit embodies the usual folding mechanism including a pair of folding

cylinder 11 and 12 mounted on the frame of the unit 10, and also a pair of nipping rolls 13 also supported by this frame directly over the folding couple. This is used in conjunction with the two formers 14 and the former rolls 15 and the nipping rolls 16 placed directly below the nose of the former and mounted in a stationary position on the frame of the machine.

In the position shown in Fig. 1, the two webs from the two formers are run directly from the nipping rolls 16 to the nipping rolls 13 of one of the folding units which nip them at their margins and direct them in a short straight path into the folding couple. In this way the two webs are collected at the left side as shown in Fig. 1.

When it is desired to collect them on the right side the other folding unit 10 is used as shown in Fig. 2, and it will be seen that the relationship between the nipping rolls 13 and the folding couple is the same as in the position shown in Fig. 1. However, the run of the webs is different. On each side the folders are so located that the margins 17 of the webs coming from both formers will meet and register with the folder without the necessity of running either of them over compensating rollers. As the margins on one half the webs are staggered with respect to those on the other half, it is necessary to place the folder in each of the positions shown out of line. Thus when associated between the nips of the rolls 13 directly over the folder unit they will register directly, as is indicated.

In this way tabloid papers with their slit edges can be run through to either of the two folders without material puckering or gathering of some of the webs folded outside the others. Also the compensating rollers with their supporting parts are eliminated altogether and the nipping rolls which are a part of the folding mechanism are mounted in stationary bearings, or such bearings as may be desired to adjust them, without providing for the long adjustments necessary in many cases for the usual compensating rollers.

only a single form of the invention I am aware of the fact that modifications can be made therein by any person skilled in the art without departing from the scope of the 5 invention as expressed in the claims. Therefore, I do not wish to be limited to the exact form shown, but what I do claim is:—

1. In a newspaper folding machine, the combination with a pair of formers and their 10 nipping rolls for receiving and directing two webs, of a folding unit located at one side of the center, a frame for said unit and a pair of nipping rolls carried by said frame independently of the formers and directly 15 over the folding unit for receiving the webs from both of the pairs of nipping rolls on the formers.

2. In a folding machine for a newspaper printing press, the combination with a pair 20 of formers for receiving the two halves of a slit web, and nipping rolls associated with the formers and in line with the noses thereof, of a folding unit having a folding couple, a frame for said unit and a pair of nipping rolls carried by said frame directly over 25 the folding couple and receiving the two webs directly from the nipping rolls of the two formers.

3. In a folding machine for a newspaper 30 printing press, the combination with a pair of formers for receiving the two halves of a slit web, and nipping rolls associated with the formers and in line with the noses thereof, of a folding unit having a folding couple, a frame for said unit and a pair of nipping rolls carried by said frame directly over 35 the same and receiving the two webs directly from the nipping rolls of the two formers, the second pair of nipping rolls being located out of line with the first pair, for the 40 purpose described.

4. In a folding machine of the character described, the combination with a pair of 45 formers for receiving the two halves of a slit web and two pairs of nipping rolls, one pair directly in line with the nose of each former, of a folding unit having a pair of nipping rolls associated therewith to deliver always 50 directly between the cylinders of the folding couple and located directly over the folding couple in such position that the margins of the two webs coming from the two formers will meet and register on a transverse collect run.

5. In a folding machine for tabloid newspapers, the combination of two formers and 55 two folders, said formers each having a pair of nipping rolls carried thereby and located directly in line with the nose of its respective former, a frame for said folders, said folders each having a pair of nipping rolls associated therewith and carried by said frame and located directly above the folder 60 for receiving the slit webs directly, so that

each folder will receive the halves of the slit web with their margins in registration.

6. In a folding machine for tabloid newspapers, the combination of two formers, two 70 folders for receiving the slit webs directly, said folders and formers being so located relatively to each other that each folder will receive the two halves of the slit web and means adjacent to the folders for causing the webs to be led into the folder with their 75 margins in registration.

7. In a folding machine the combination of a plurality of formers, a movable transverse folding mechanism so arranged relatively to the formers that the folding mechanism may be adjusted with respect to the formers and nipping rolls carried by the folding mechanism so that the margins of the products of the formers shall register 80 when entering the transverse folding mechanism.

8. In a folding machine, the combination of two formers, each for receiving one half 85 of a newspaper web, a transverse folder, said folder being movable laterally across the machine and means for directing both half webs into said folder.

9. In a folding machine for folding tabloid newspapers, the combination of two parallel 90 formers for receiving the two slit halves of the web, a folder movable laterally across the machine, and means for directing the half webs from the two formers into the folder in two positions thereof.

10. In a folding machine, the combination 100 with two formers in fixed position for receiving the two halves of a split web, and a transverse folder movable to a position out of registration with either former in which the margins of the two webs will register with 105 each other as they pass into the folder.

In testimony whereof I have hereunto affixed my signature.

OSCAR CHARLES ROESEN.
